UNITED STATES PATENT OFFICE.

EMILE BLAESIUS, OF NEW YORK, N. Y.

ADJUSTABLE PLAQUE-STAND.

SPECIFICATION forming part of Letters Patent No. 326,387, dated September 15, 1885.

Application filed July 28, 1885. (No model.)

To all whom it may concern:

Be it known that I, EMILE BLAESIUS, of the city, county, and State of New York, have invented a new and Improved Adjustable Plaque-
5 Stand, of which the following is a full, clear, and exact description.

My invention consists of a novel plaque stand or support for pictures, made adjustable to hold the picture at the proper angle or pitch
10 to cause it to show to the best advantage in any light, all as herein after fully described, and pointed out in the claim.

Reference is to be had to the accompanying drawings, forming part of this specification, in
15 which similar letters of reference indicate corresponding parts in all the figures.

Figure 1 is a broken side elevation of my new and improved plaque or picture stand as it appears when holding a plaque. Fig. 2 is a
20 front elevation of the stand; and Fig. 3 is a detailed sectional elevation showing a modification of the adjusting-leg.

A represents my new plaque or picture stand, and B represents a plaque placed upon
25 the stand. The stand A is composed of the curved legs *aa*, upper cross-piece, *b*, and adjustable rear leg, *c*. The front legs, *aa*, are curved to form the hooks *a'*, for retaining the plaque or picture, as illustrated in Fig. 1, and they are
30 preferably made in one piece with the cross-piece *b*. At the back of the cross-piece *b* is

formed the lug *b'*, which has an opening, *b*², made through it to receive the upper end of the rear leg, *c*. In the form of stand shown in Figs. 1 and 2 the opening *b*² is a plain round 35 opening to receive the rounded portion *c'* of the rear leg, *c*, and in the lug *b'* at the back is fitted the set-screw *d*, by which the rear leg, *c*, may be held at any desired position. In the form of stand shown in Fig. 3 the opening *b*² is screw-threaded, and the upper end of the leg *c* is screw-threaded to match, so that by turning the leg *c* the pitch of the stand may be varied as desired. By loosening the nut *d* the stand may likewise be adjusted. 40
45

In this manner the stand may be adjusted to hold any picture, and to hold it at any angle to suit any light to make the picture show to the best advantage, and the stand is at the same time cheap and practical. 50
55

Having thus described my invention, I claim as new and desire to secure by Letters Patent—

The stand A, having the curved and hooked legs *aa*, made in one piece with the cross-piece *b*, in combination with the vertically-adjustable rear leg, *c*, held in an opening made in the cross piece *b*, substantially as described.

EMILE BLAESIUS.
